UNITED STATES PATENT OFFICE.

JACK IMBER, OF LONDON, ENGLAND.

MEANS FOR LOCKING DOORS.

Application filed January 14, 1926. Serial No. 81,208.

This invention relates to means for locking the doors of automobile vehicles, railway carriages and the like and has for its object the provision of an improved construction and arrangement designed to ensure positive engagement of the locking devices when a door is closed, to prevent rattle, to prevent opening of a door by vibration and to provide a locking mechanism which will compensate automatically for wear of the interengaging parts and for warping and other causes liable to effect relative displacements between a door and its mounting or framework.

According to the invention, a lock for doors and the like is provided comprising fixed and movable elements disengaged when a door is open and each formed with curved or inclined surfaces so arranged that the movable element centres itself automatically within the fixed element when the door is closed. According to the preferred form of the invention a bolt carried by a door is formed with a curved and recessed end portion adapted to engage under spring pressure, when the door is closed, in an annular socket having a central tapered projection adapted to fit the recess in the bolt.

Reference will now be made to the accompanying drawings which illustrate by way of example a construction according to the invention and in which:—

Figure 1 is a side elevation of the lock,
Figure 2 is an elevation of the striking plate,

Figure 3 is a sectional plan showing the position of the bolt when the door is partly closed and

Figure 4 is a sectional plan showing the position of the parts when the door is completely closed.

The construction illustrated is intended more particularly for application to the door of an automobile vehicle and comprises a bolt *a* forming part of a lock mechanism of any suitable type enclosed within a casing *b* having at one end a perforated plate *c* by which the lock can be attached to the edge of a door *d* (Figure 3) in the usual manner. The bolt *a* is normally maintained in the position shown in Figures 1 and 3 by means of a spring (not shown) against the action of which the bolt may yield inwardly during opening and closing of the door. For the purpose of retracting the bolt *a* to open the door a handle *e* operable from the ex-

terior of the vehicle and a lever *f* operable from the interior of the vehicle are provided but the bolt is only maintained in the retracted position for as long as either of the operating members is held in the necessary position. In addition to the members *e* and *f* a key-operated device may be provided to lock the bolt *a* in the operative position shown in Figure 4.

The outer end of the bolt *a* is of a cylindrical form and is provided with a conical or other form of tapered recess *g*, the outer edge of the bolt being rounded as shown at *h* to form part of a continuous curved surface between the cylindrical portion of the bolt and the interior of the recess *g*. When the door *d* is closed the bolt *a* co-operates with a striking plate *i* formed or provided with perforated lugs *j* by means of which the striking plate is fixed in position on the end of the vehicle frame or body *k* against which the edge of the door *d* abuts when closed. The outer portion of the striking plate terminates in a sharp edge *l* beyond which extends an outwardly inclined portion *m* beyond which lies an outwardly curved surface *n* leading to a flat portion *o* in which is formed a socket *p*, the centre of which is provided with a tapering projection *q* adapted to fit into the recess *g* in the bolt *a*.

The operation of the device above described is as follows:—

When the door *d* is moved towards closed position the outer end of the bolt *a* comes into engagement with the edge *l* of the striking plate, the spacing of which from the plate *i* is sufficient to allow the end of the bolt to ride over the edge *l* onto the inclined portion *m*, this operation being aided by the curved edge *h* of the bolt. Continued pressure on the door causes the end of the bolt to travel along the inclined portion *m* as shown in Figure 3 and over the curved portion *n*, the bolt meanwhile yielding inwardly (that is towards the right, Figures 1, 3 and 4) against the action of its spring until the bolt is brought into axial alignment with the socket *p* into engagement with which the bolt is forced owing to the spring being free to expand when the bolt reaches the position shown in Figure 4. As the bolt moves outwardly its recess *g* is engaged by the projection *q* and should the bolt have deviated from its correct position through any cause it is centred automatically by the projection

g operating in conjunction with the pressure exerted by the spring.

To ensure that the bolt makes full engagement with the fixed socket the devices above described are so proportioned that the distance between the outer end of the bolt *a* and the plate *c* when the door is open is greater than the distance between the base of the socket *p* and the plate *c* when the door is closed. When, therefore, the parts are in the relative positions shown in Figure 4 the bolt is maintained by the spring in close engagement with the socket thus preventing rattling of the door when closed. By proportioning the parts in the manner described the spring is also enabled to operate to compensate for wear on the interengaging surfaces of the bolt and socket whilst as a further provision for such wear, the bolt may be proportioned so that when first put into use it will not quite reach to the base of the socket when the parts are in the position shown in Figure 4.

It is preferred that the bolt and socket should be designed in such a manner that the angle made by the engaging surfaces of the socket *g* and projection *q* with the axis of the bolt *a*, whether the bolt is completely centred or not, will be less than 45 degrees, thus ensuring that the door will be positively fastened in closed position by the bolt in all conditions, but this angle must not be small enough to allow the projection *q* to become tightly wedged in the socket *g*. It will be understood that the invention is not limited to the particular application above described but may be applied to any door or closure adapted to be fastened by means of a sliding bolt. Moreover, forms of construction other than that described with reference to the drawings, but provid-

ing co-operating curved or inclined surfaces adapted to render a bolt self-centring may be used without departing from the invention. For example, the bolt may be flat instead of cylindrical but otherwise presenting the shape shown in plan in Figure 4 and engaged by a correspondingly shaped socket when in closed position.

I claim:—

1. A lock for doors and the like, comprising a movable bolt on the door of cylindrical form and provided with a tapering socket at the outer end, and a fixed striking plate having a socket into which said bolt springs, and centering means in said plate socket for said bolt, the outer edges of the bolt socket and of the bolt being rounded to facilitate engagement with said striking plate and its socket.

2. A lock for doors and the like comprising a movable bolt on the door of cylindrical form and provided with a socket at the outer end, and a fixed striking plate formed with curved surfaces and with an annular socket, the center of which has a tapering projection adapted to enter the socket of said bolt when the door is closed.

3. A lock for doors and the like comprising a cylindrical bolt slidably mounted in a door and urged outwardly by a spring, a tapered recess formed in the end of said bolt, a fixed striking plate having curved surfaces adapted to press the bolt inwardly as the door is moved towards closed position and having an annular socket surrounding a tapered projection adapted to center the bolt automatically as the door reaches closed position when the spring forces the bolt into locking engagement with the socket.

In witness whereof I affix my signature,
JACK IMBER.
